SANITARY NAPKIN MACHINE

Curt G. Joa, Manitowoc, Wis., assignor to Curt G. Joa, Inc., Manitowoc, Wis., a corporation of Wisconsin

Application December 16, 1935, Serial No. 54,689

33 Claims. (Cl. 154—29)

This invention relates to improvements in sanitary napkin machines.

It is the primary object of the invention to effect great economies in the manufacture of sanitary napkins while improving substantially the quality of the napkins produced. In the machine herein disclosed this objective has been attained by several outstanding features of novelty including the following:

10 In the first place, the speed of operation has been approximately doubled as compared with previously existing equipment while, at the same time, the quality of the product has been improved. One of the contributing factors has 15 been an arrangement whereby the feed of cellucotton is substantially continuous. The elimination of the intermittent feed previously employed avoids compression and distortion of the material and enables a much higher rate of speed 20 to be maintained throughout the machine. Another contributing factor is the arrangement whereby the pads severed from the cellucotton web are turned about and spaced by simple mechanical means which does not distort the pads 25 nor get out of order. Another contributing factor consists in the arrangement whereby an entirely new mechanism is employed for cutting the folded gauze between the pads which have been enfolded therein, the cutting operation 30 being performed at high speed without interrupting the continuous steady movement of the gauze and pads. Still another contributing factor is the arrangement whereby the completed napkins delivered from the machine are automatically piled in stacks and discharged in 35 proper condition for packaging.

In the second place, shut-downs have been substantially eliminated. Largely contributing to this end is the arrangement whereby continuous motion is substituted for a reciprocating feed. Another important contributing factor is mechanism whereby the cellucotton web is assembled in the operation of the machine from rolls which supply portions of the web in staggered relation, 45 each such portion being independently replaceable when exhausted to maintain the web of cellucotton in continuous feed with substantially no waste. The simplification of the machine and the reliability of the mechanisms employed 50 are such as practically to eliminate shut-downs due to breakage or stoppage.

In the third place, the mechanisms hereinafter to be disclosed are so fully automatic as to cut down the number of operators from about five 55 for prior art machines to the number of two

required for the operation of the present machine.

Finally, the amount of waste is very materially reduced in the present device due to the novel cellucotton feed which practically eliminates 5 faulty pads and consequently saves not only the pad material but also the much more expensive gauze which has heretofore been wasted whenever a pad has been spoiled in the previous machine.

10 In addition to simplification and improvement in reliability, it may be stated more specifically that the objects of the invention include the provision of a novel pad material feed; the provision of means whereby the motion of the pad material and the wrapping material is continuous throughout the machine; the provision of novel means for turning and advancing the pads; the provision of means whereby the longitudinally folded gauze and the pads contained therein 20 are inverted so that the end fold may be made on the same side of the pad as the longitudinal fold; the provision of a novel gauze cut-off and end fold; the provision of a novel stacker; and, finally, the very important provision of means 25 whereby the need for synchronization of the various parts of the machine is eliminated, the work being repeatedly timed automatically in its progress through the machine to do away with the constant attention of operators and the faulty 30 product always attributable to the impossibility of keeping the various parts of a complex machine in synchronous operation.

In the drawings:

Figure 1 is a diagrammatic view in perspective 35 illustrating the general relation of the component parts comprising my improved sanitary napkin machine.

Figure 2 is a view in longitudinal section showing that portion of the machine in which the pads 40 are blanked from the cellucotton web and turned for endwise delivery through the remaining portion of the machine.

Figure 2a shows a modified blanking die construction in longitudinal section.

Figure 3 is a plan view of the apparatus shown in Figure 2.

Figure 4 is a view partially in longitudinal section and partially in side elevation of that portion of the machine in which the pads are fed to 50 the gauze, the gauze is folded thereabout, the gauze and pads are inverted, the gauze is severed between the pads, and the first end fold is made.

- Figure 13 is a view taken in section on the line 13—13 of Fig. 12.
- 25 Figure 14 is a detail view in section of an overrunning clutch used in the cut-off device.
- Figures 15 to 19 are views diagrammatically illustrating a complete cycle of operations of the die set in the movement of the dies to and from each other and their concurrent movement along the path of cellucotton travel.
- Figure 20 is a view in transverse section through the mechanism which stacks the sanitary napkins for delivery from the machine.
- 35 Figure 21 is a view of the stacking and delivering mechanism taken on line 21—21 of Fig. 20.
- Like parts are identified by the same reference characters throughout the several views.
- It is conventional practice to cut a sanitary napkin pad 15 from a web of cellucotton 16 which may comprise some 36 plies of crepe tissue paper. The web is approximately equal in width to the length of the finished pad, each successive pad being severed from the advancing end of the web.
- 40 In the past the web has been fed intermittently and in one piece. In accordance with the present invention feed of the web is continuous and the web is assembled on the machine from a number of separate webs of lesser thickness. Thus, to produce a 36 ply web, I prefer to use three parent rolls 17, 18 and 19, which may be of 12 ply paper unrolled in staggered relation so that only one such parent roll will become exhausted at any given time.
- 45 55 Where only one third of the completed web 16 terminates at any one time, the operator can join the butt of another roll to such end without stopping the machine and without interfering with the production of acceptable pads. By this one means the present invention overcomes a source of waste which, in the operation of some sanitary napkin machines, has reached enormous proportions.
- In the present machine the cellucotton web is not compressed or distorted by starting and stopping its motion. Beneath each of the combination webs is a feeding belt 20, at the delivery end of which is a co-acting feed belt 21. These belts are in continuous and uniform motion to advance the cellucotton web steadily to the blanking die which cuts the individual pads from the end thereof. This die appears in detail in Figs. 2 and 3.
- Beyond the end of the conveyor 20 the web 16 receives support from a plate at 22, the end of which rests slidably on the apertured die block 23. This die block is mounted on a carriage 24 so guided on a stand or pedestal 25 as to be reciprocable longitudinally beneath the path of the advancing cellucotton web 16. It is caused to reciprocate by means of eccentric 26, eccentric strap 27, link 28, lever 29, and link 30.
- Upon each retrogressive reciprocation with respect to the advancing web 16, the die block 23 passes beneath the end portion of the web so that such end portion registers with the die opening 31 therein. In the opposite direction of reciprocation the die member 23 moves with the web and at substantially the same speed. The total range of movement of the carriage is only approximately one half of the width of the pad or about $1\frac{1}{2}$ " in the production of a conventional 3" pad.
- Guided for movement vertically upon the carriage 24 by means of the posts 32 is an operating head 34 provided with a link 35 which connects it with crank 36 mounted on the same shaft which carries the eccentric 26. Thus, as the carriage 20 moves forwardly with the cellucotton in the manner shown in Figs. 2 and 3, the head 34 is being moved concurrently in a downward direction. Removably mounted thereon is a punch or die 37 complementary to the aperture 31 of die member 23 and preferably having a concave lower surface so that it does not operate simultaneously on all of the margins of the pad blank severed thereby. As the carriage advances, the die descends until ultimately it passes through the aperture 31, thereby severing from the end of the cellucotton web 16 a pad or blank having the shape of the aperture 31 and the die 37 and also severing both from the web and the blank a roughly triangular piece of waste from both corners of the end of the web.
- The only portions of the cellucotton separated both from the parent web and from the blank are these outer corners which are left on top of the die or table member 23 to be removed therefrom either by the operator of some convenient suction appliance.
- The plunger or die member 37 is preferably made hollow and provided with a knock-out device at 39 actuated by means of a rod 40, link 41, slide 42, pin 43, and stop 44 to ensure the release of the pad after the die member 37 has passed through die member 23.
- In Fig. 2a I have shown the die member 37 made solid and operated without a knock-out device, its construction and operation being otherwise identical with the construction shown in Fig. 2.
- It will be understood that at the time the die operation occurs, the supporting die or table 23 is moving with the cellucotton web 16 and the die member 37 is not only moving with said web in a longitudinal direction, but is moving across its path in a vertical direction. Thus, the resultant motion of die member 37 is almost circular and the pads are successively severed from the web without mutilation thereof and without the slowing down of the machine, such as is required in the operation of a reciprocatory feeding device working on paper.
- The timing is preferably such that the blanking operation is performed during the continuance of the concurrent forward motion of carriage 24 with the advancing web 16, such motion continuing while the punch die 37 is retracted upwardly out of the path of the web. It is only after the punch die clears the advancing web that the carriage begins its rearward movement to bring the matrix die 23 beneath the web in registry with the next blank portion. Figs. 15 to 19

show diagrammatically a cycle of operations of the table and die.

The completed pad, thus blanked out from the advancing web 16, falls on to a longitudinally slotted conveyor table 45, best illustrated in Fig. 3. In its original position the pad 47 is disposed transversely of the conveyor table 45 and lies across the three slots with which the table is preferably provided. Operating in the slots are conveyor chains 48, 49 and 50. The conveyor chains 48 and 49 may be of approximately the same length, but conveyor chain 50 is materially shorter than chain 49 for a functional reason. Chains 48 and 50 have conveying fingers 51 and 52 correspondingly located to engage the pad adjacent both of its ends to propel it along the conveyor table 45 while still in a transverse position thereon. Chain 49 also has conveying fingers at 53, but these are not in registry with the fingers 51 and 52, so that the pad is initially propelled only by chains 48 and 50.

Immediately beyond the point at which propulsion of one end of the pad by chain 50 ceases, the table surface is provided with an obstruction 55 which may take the form of a pin 55. Thus the end of the pad originally propelled by chain 50 is not merely relieved of such propulsion, but is positively interrupted as to movement while the other end of the pad continues to be propelled by the conveyor chain 48 and the lugs 51 thereon. The lugs preferably have curved terminal ends, as clearly shown in Fig. 3, so that they will not dig into the pad as the pad begins to swing about the obstruction 55 upon which it tends to pivot.

The continued movement of conveyor 48 ultimately turns the pads for a full ninety degrees, the distance between each of the lugs 51 and the obstruction 55 being approximately equal to the width of the pad. To ensure the longitudinal alignment of the pad with the center line of the table 45, the table is also preferably provided with a shallow channel at 56 which is spanned by the pad while it still remains transverse with respect to the table, and into which the pad ultimately is deposited by its swinging movement about the obstruction 55.

As soon as the pad drops into the channel 56 it is no longer contacted by the conveyor lug 51 of chain 48, and accordingly it is momentarily without any means of propulsion. Almost immediately, however, it is picked up by one of the lugs 53 of the central conveyor 49, and is thereby discharged from the table 45 on to a smooth metallic chute 57 along which the pad is propelled at high speed by the lower flight of a high velocity conveyor 58 which engages the pad from above. It will be noted from Fig. 3 that the pads are rather close together as deposited on table 45, and their ends are even closer together when the pads are aligned in trough 56. The high velocity movement of conveyor 58, however, separates the pads at substantial distances in the conveyor trough 57.

Up to this point it is only necessary that the pads be made with sufficient rapidity, and no accurate timing of pad delivery is required. The means which delivers the pads in properly spaced position upon the gauze will now be described.

Reference is made to Figs. 4, 5, 6, and 7 of the drawings, and also to Fig. 1.

From a parent roll 60 of gauze, the gauze web 61 is led over the guide rolls 62, 63, 64, and 65, on to a folding table 66 longitudinally channeled at 67 at the width of the channel corresponding to that of the pad. The downward movement of

the gauze web about rolls 62 and 63 accommodates a pad feeding table 68 having guides 69 between which the successive pads 15 are discharged from the conveyor trough 57 by belt 58. The feeding table is slotted at 681 to permit the projection by lug 69 of a timing conveyor 70. If these lugs remain radial with respect to the sprockets 71 about which they pass in withdrawing from propulsive relation to the pads, they would tend to draw the ends of the pads with them into the slot 681. Accordingly means is provided as best shown in Fig. 7, for holding these lugs upright during this portion of their travel. Each lug is pivoted at 72 to the conveyor chain and has arms 73 extending rearwardly along the chain and provided with laterally projecting pins 74 confined in a suitable guideway 75. As the chain starts about the sprocket 71 the pins 74 remain horizontal and prevent the propelling lugs 69 from assuming the radial position which they would assume if they were fixed to a given link of the chain.

The two lugs 69 of conveyor 70 deliver the successive pads in properly spaced relation on to the gauze web 61 in line with channel 67 of the folding table. Due to this arrangement any discrepancy in the timing of the different parts of the machine is corrected at the moment the pad is discharged on to the gauze, and there is no possibility for a pad to reach the gauze in any way other than in a position of proper alignment and proper spacing.

More or less conventional triangular folding boards 76 and 77 turn the side margins of the gauze web 61 over the pad. The proper feeding of the gauze margins across the folding boards 76 and 77 is ensured by a set of controlling rollers 78, the surfaces of which are preferably knurled for better engagement with the gauze. These rollers are mounted rotatably on the ends of arms 79 which are fulcrumed at 80 to suitable supports at the sides of the folding table and are held locked in their operative position by catches engaged with the arms at 81. The arrangement is such that there is nothing exposed which could catch on the gauze or interfere with its smooth feeding over the folding boards.

As the pads leave the folding table 66 they are enfolded between the overlapping margins of a continuous ribbon 84 of gauze. The space between pads in such ribbon is sufficient to provide the necessary free gauze ends for the completed sanitary napkins. Ultimately the ribbon is to be severed between pads and the resulting free ends of folded gauze are to be folded over the body of the pad to complete the napkin. Since it is desirable that the ends of the gauze ribbon be folded on to the same face of the pad on which the free side margins of the gauze have already been folded, and since the folding operation is conducted beneath the pad, it is desirable to invert the pad before cutting the gauze ribbon and folding the ends.

The gauze ribbon 84 and the interfolded pads are drawn from the end of the folding table 66 about a pulley 85 having its periphery relieved or cut away at 86 to accommodate the pads so that they will not be compressed in passing about the pulley. The conveyor belt 87 is in pressure relation to the pulley and the ribbon 84 on the unrelieved surfaces thereof, and furnishes propulsive traction to draw the gauze and interfolded pads about the pulley. Beyond the pulley the gauze ribbon and pads are supported on the belt 87 in their movement to the shearing and

folding mechanism next to be described. In passing about the pulley 88 the folded gauze ribbon has become inverted so that the overlapping margins originally at the top of the ribbon are now at the bottom thereof.

In my Patent No. 1,957,651 issued May 8, 1934, I have described an end folding mechanism for sanitary napkins which embodies some of the principles used in the present device. The present device is, however, modified to incorporate a web shearing device which actually co-operates in the folding of the ends. The mechanism is shown in Figs. 1, 5 and 6, and appears in enlarged scale in Figs. 8 and 9.

15 The flight of supporting conveyor belt 87 upon which the folded gauze ribbon and the enfolded pads are traveling terminates abruptly in passing about the pulley 88. There is a slight gap between pulley 88 and the pulley 90 over which 20 operates the conveyor belt 91 which is next to receive the gauze ribbon and pad. This gap is substantially less than the length of the pad and the pad is sufficiently rigid so as to tend to be projected linearly across the gap from conveyor belt 87 to conveyor belt 91.

25 In the gap between the two conveyors is a stationary shear knife 92 sufficiently low so that it will easily be cleared by the pad and gauze in their movement across the gap, but sufficiently 30 high so that the gauze will be supported on the shear bar 92 during the shearing operation. The shear bar 92 is set at an angle best shown in Figs. 5 and 9.

35 Co-acting with shear bar 92 is a rotary shear mechanism with a step by step actuator. The rotor 94 preferably has four radial arms upon which the shear blades 95 are mounted. The rotor 94 is adjustably mounted on shaft 96 so that a proper setting of the blades 95 with respect 40 to the stationary shear 92 may be had. The shaft 96 is at an acute angle with respect to the longitudinal center line of the machine, so that the path of rotation of the blades 95 will correspond to the angle of the stationary shear 45 92.

The shear is normally held with its blades in the relative position shown in Fig. 8 by means of a dog 97 which engages notches 98 in the periphery of the drum-shaped portion 99 of rotor 50 94. The dog 97 is pivoted at 100 and has an arm 101 which may be engaged by the lever 102 of the shear operating mechanism to release the dog in preparation for their movement.

55 Lever 102 is connected by link 103 with the arm 104 and a ratchet feeding device 105 which has clutch balls 106 spring pressed to engage shaft 96 of the rotor in a well known manner. As viewed in Fig. 14, a clockwise movement of the ratchet actuator 105, however, by arm 102, will 60 first release the holding dog 97 and will subsequently move the rotor 94 approximately 90 degrees. This will shear the folded ribbon of gauze overlying the stationary shear blade 92, and the rotor will again come to rest in a position determined by dog 97. The return movement of the actuator 105 in a counter-clockwise direction as viewed in Figs. 14 and 8, will have no effect on the rotor.

70 The movement of the operating lever 102 for the shear mechanism is preferably produced electrically by means of a solenoid 110 having an armature 111 connected by rod 112 and link 113 with the lever 102. The operation of the solenoid is controlled by a switch having an actuating lever at 115 which rests on the lower flight of

conveyor belt. The supporting flight of conveyor belt 87 is held at this point by a table 116 so that it cannot yield downwardly.

Consequently, each successive pad which passes between the supporting table 116 and the shoe 5 117 of switch lever 115 will simply lift the switch lever as shown in Fig. 4, thereby completing the circuit to solenoid 110 and operating the cut-off knife which severs the gauze ribbon ahead of the next preceding pad. The switch mechanism 118, the table 116, and the switch operating lever 115 are preferably assembled in a unit which is adjustable longitudinally so that the solenoid may be timed for operation at any given relative distance between pads.

15 The moving shear blade 95 obviously enters the moving gauze ribbon adjacent its left hand margin as viewed in Fig. 9. The ribbon is not stopped, but continues in uniform movement during the shearing operation. The angularity of 20 the shear blades is so determined with reference to the speed of movement of the gauze that as the shear cut progresses from the left hand side of the gauze to the right hand side thereof, the movement of the gauze will exactly compensate 25 for the angle of the blades, thus producing a 90 degree transverse cut in the gauze ribbon.

The cut-off knife 95 shears the gauze ribbon between pads and positively thrusts the free end 160 of the gauze downwardly in the gap between the conveyor pulleys 88 and 90. As the succeeding pad spans the gap and is engaged by conveyor 91, the free end 160 of the gauze ribbon is drawn up beneath the pad to complete the first end fold. The trailing end 161 of the gauze remains 35 to be folded. Co-acting with conveyor 91 to complete the first end fold is an upper conveyor 162.

In Figs. 10, 11, and 11a I have shown modified embodiments of this portion of the mechanism, 40 wherein the knife is positively driven in timed relation to the conveying mechanism and a different type of propulsive conveyor is used.

A conveyor table 164 supports the conveyor belt 87 for a considerable distance in advance 45 of the pulley 88. Opposed to the portion of belt 87 thus rigidly supported, is a propulsive conveyor 165 consisting of a chain operating over sprockets 166 and 167 and carrying a plurality of separate series of pressure blocks 168. The separate series 50 are spaced from each other so that the blocks will engage the spacers between the pads to hold the folded gauze on to the belt 87 without compressing the pads. Where the distance between successive pads is changed a different propulsive 55 conveyor chain 165 is substituted to have the correct number of pressure blocks to fit the space between pads.

The stationary cut-off knife 92 may be identical with that already described and shown in Figs. 60 4 and 5. It is preferably set angularly across the path of movement of the gauze to compensate for the time required for the cut to penetrate from one side margin of the gauze to the other, so that the resulting cut will be square. 65 Instead of the plurality of blades driven intermittently, the present cutter comprises a single blade 169 driven continuously. It is mounted on an arm 170 carried by a shaft 171 driven by chain 172, gearing 173, and chain 174, in synchronized relation to the gauze feeding means. The movable knife is adjusted to the fixed knife by means of an adjustable thrust bearing 173a to which the shaft 171 is pressed axially under the yieldable pressure of compression spring 174a. 75

The second end fold is made by mechanism essentially corresponding to that which makes the second end fold in the construction shown in the aforesaid Patent No. 1,957,651. Accordingly, it is not described in detail here, but it is diagrammatically illustrated in Fig. 1. The conveyor 163 operates at a somewhat higher speed than conveyors 91 and 162, and to prevent this increase in speed from unfolding the first end fold of gauze, 10 the friction wheel 119 is used between the two conveyors to accelerate the movement of the pad to the rate of speed of conveyor 163.

Conveyor 118 has a sharp change of angle at 120 just beyond which, in spaced relation to the belt, are retractable slides 121 which are controlled by a solenoid that is not shown here but is similar to solenoid 110 which operates the cut-off knife. The switch lever controlling the circuit to this solenoid is indicated diagrammatically at 122 in Fig. 1. As the pads and the gauze having its first end fold about the pad are carried by conveyor 163, they are projected by the change in angle of the conveyor on to the plates 121 which support the pad and the first end fold 25 temporarily. The static which causes the adherence of the trailing gauze end 161 to the belt carries such end beneath the pad as the pad is supported on the plates 121 and thereupon the engagement of the next succeeding pad with 30 switch trigger 122 operates the solenoid to retract the plates 121 and to drop the pad on to the unfolded trailing end 161, thus completing the second end fold. The completed and folded sanitary napkin shown at 125 is then discharged into 35 a stacking device now to be described with particular reference to Figs. 20 and 21.

The curved guides 127 are bands arranged in pairs, the respective pairs being spaced the width of a pad, and lead to a trough 128 from which the stacked pads may be withdrawn. At their upper ends the curved guides 127 comprise a feeding throat through which the pads may enter between the guides 127 to be packed therein between the end guides 175. Between the guides of each pair at each side of the throat are chain conveyors 130 with projecting arms 131. The upper centers on which the chains 130 operate, are sufficiently close together so that said arms almost meet at 132 to provide a receptacle into which the completed sanitary napkin is discharged from belt 163. The lower centers about which the chains 130 operate, are spaced more widely apart so that as the belts are actuated to move each successive napkin downwardly, the lugs 131 gradually withdraw from beneath the napkins, allowing them to be deposited between the fingers 129 which are yieldable and project inwardly from guides 127 to offer sufficient resistance to napkin movement so that the napkins 60 are held in a stack and advanced only under pressure.

When the stack builds up sufficiently so that the uppermost napkin thereof is engaged by the under surfaces of the arms 131 prior to their complete retraction, such arms will have a feeding movement upon the napkins of the stack to force them through the throat until a predetermined number of napkins accumulate therein.

Operating over sprockets on the same shaft 176 70 which guides one of the chain conveyors 130, is another chain conveyor comprising chains 178 carrying the paddles 180 at spaced points along its course. The spacing between these paddles is such that after a sufficient number of napkins is accumulated between the yieldable fingers 129, a pad-

5 idle carried by each chain 178 will engage the opposite ends of the uppermost napkin in the stack to propel the stack between guide members 127 and 175 to the discharge trough 128. Idler pulleys are provided for chains 178 so that they may 5 follow the path of the napkins. One of the idler pulleys 181 is made adjustable as a tightener for the chains 178, the guide members 127 and 175 being flexibly adjustable and adjustably supported at 182 so that their curve will conform 10 to the adjusted curve of the chains.

The driving connections for the stacker and counter as above described, are clearly shown in Figs. 20 and 21, but need not be described in detail except to say that the driving chain 184 is 15 connected with the actuating mechanism for the remainder of the machine to be driven in synchronization therewith so that the supporting arms 131 will always move into registry at 132 to receive each napkin completed and delivered on the 20 conveyor 163.

Some of the chain connections preferably used for operating the various parts of the machine are indicated in Figs. 2 and 3 of the drawings. They will not be described in detail since any operative mechanical driving connections may be 25 employed. It is particularly to be noted that no accurate timing system common to the whole machine is necessary, since each important operation is synchronized directly with reference to the 30 pads themselves. As above noted, the spacing between pads is determined by the movement of the conveyor 70 with reference to the movement of the gauze. To produce changes in rates of relative movement between one belt conveyor and another, 35 I may employ a belt driving pulley of variable cross section as shown in Figs. 12 and 13. The driving shaft 142 carries a sleeve 143 having right and left threaded portions with which cones 145 and 146 are engaged. Each cone has a series of 40 uncut T-shaped slots at 147 in which operate complementary slides 148 connected by screws 149 with pulley sectors 150. These sectors are covered by an elastically contractile pulley covering 151 which spans the joints between the sectors when 45 the latter are expanded.

The chains 130 preferably have a step by step actuation by means of solenoid 134, armature 135, connecting rod 136, link 137, lever 138, link 139, and a suitable ratchet mechanism 140 which may 50 correspond to that which operates the cut-off knife. The solenoid 134 may have its own trigger switch with a trigger at 141, or it may be operated from the trigger 122 which controls the second end fold.

Some of the chain connections preferably used for operating the various parts of the machine are indicated in Figs. 2 and 3 of the drawings. They will not be described in detail since any operative mechanical driving connections may be employed. 60 It is particularly to be noted that no accurate timing system common to the whole machine is necessary, since each important operation is synchronized directly with reference to the pads themselves. As above noted, the spacing between 65 pads is determined by the movement of the conveyor 70 with reference to the movement of the gauze. To produce changes in rates of relative movement between one belt conveyor and another, I may employ a belt driving pulley of variable 70 cross section as shown in Figs. 12 and 13. The driving shaft 142 carries a sleeve 143 having right and left threaded portions with which cones 145 and 146 are engaged. Each cone has a series of uncut T-shaped slots at 147 in which operate 75

complementary slides 148 connected by screws 149 with pulley sectors 150. These sectors are covered by an elastically contractile pulley covering 151 which spans the joints between the sectors 5 when the latter are expanded.

A lock nut 152 holds the parts in any given adjustment. When the lock nut is released and the pulley is turned with reference to shaft 142, the cone-shaped expanders 145 and 146 move to or 10 from each other, according to the direction of relative rotation. Their movement causes the sectors 150 to move radially inwardly or outwardly, thereby enlarging or decreasing the cross section of the pulley to control the rate of belt travel with 15 respect to the driving shaft 142.

Since the spacing of the pads on the gauze is absolutely uniform at a distance depending on the relative rate of gauze movement with respect to the pad feeding conveyor 70, all other operations 20 may be timed with reference to the pads themselves. Thus, the cut-off operation is timed with the greatest accuracy by means of a switch operated by the next successive pad. The relative ratio of leading and trailing ends of gauze may be 25 varied as desired by simply adjusting this switch assembly longitudinally of the path of pad travel. Thereafter no further timing is necessary until the second folding operation is performed. This, likewise, is controlled with reference to the next 30 succeeding pad of the series, and is therefore timed entirely independently of the remainder of the machine. The stacking device likewise has its own timing.

I claim:

35 1. In a machine for the manufacture of sanitary napkins or the like, the combination with means for continuously feeding a web of cellucotton, of means for blanking pads from said web while the web is in motion, said means comprising a die set mounted for movement along the path of said web and comprising guides reciprocable with reference to each other for a cutting operation, a means for simultaneously reciprocating said dies in a cutting operation while advancing said dies with said web along said path, and subsequently separating said dies and returning 40 said set backwards along said path.

50 2. A sanitary napkin machine comprising means for continuously feeding cellucotton, means for continuously feeding gauze, means for blanking pads from the end of the cellucotton web during the continuous advance thereof, means for delivering said pads successively to said gauze in spaced relation, means for folding the gauze thereabout, and means for severing the gauze 55 between the pads during the continuous movement of the gauze.

60 3. In a sanitary napkin machine comprising means for continuously feeding the web of filling material, the combination with a die set movable forwardly and backwardly along the path of movement of said web and including a female die below the path of said web and across which the end of the web is movable, a male die movable between the retracted position above the path 65 of said web and an advance position in operative cutting relation to the female die, and means for synchronously operating said die set to and fro along said path while actuating said male die between said advanced and retracted positions, said male die being actuated to cutting position while said set is moving with said web and being actuated to retracted position while said die set is moving reversely with respect to said web.

70 4. In a machine for the manufacture of sani-

tary napkins, the combination with means for feeding a web of filling material of pad cutting mechanism including co-acting dies, means for producing relative movement between said dies for the severing of web material fed therebetween, 5 a web support connected for movement with one of said dies, and means for actuating said dies on the table to and fro along the path of web advancement in synchronism with the cutting movement of said dies, said support and dies being in 10 movement with the web during the cutting operation, and means for assembling said web comprising a plurality of parent rolls each carrying a portion of the stock required to make up said roll, the several parent rolls being of differing 15 sizes, whereby to stagger the points of termination of their several web portions.

5. A sanitary napkin machine comprising the combination with pad cutting mechanism, of means for feeding a web of filling material thereto, male and female die means for blanking pads from said web and a source of supply for said web comprising a series of parent roll supports, and parent rolls thereon each supplying a portion of the thickness of the desired web. 20

6. A machine for the manufacture of articles from cellucotton, said machine comprising male and female die means for cutting blanks from a cellucotton web, and means for assembling such a web comprising conveyor mechanism, a plurality of parent roll supports, and parent rolls on said supports having their output superimposed in said conveyor mechanism, each of said parent rolls comprising a web partially as thick as the web required to produce said blanks, and the ends 30 of the component webs of the several parent rolls being staggered.

7. A sanitary napkin machine comprising means for feeding a web of cellucotton, means for punching blanks transversely from the advancing end of said web, and means for feeding said blanks including means for pivotally turning them individually upon their respective centers while feeding them in alignment with the line of feed 40 of said web.

8. A sanitary napkin machine comprising the combination with means for feeding a web of filling material and male and female die means for cutting blanks transversely from the end thereof, of a blank feeding device aligned longitudinally with said web and including means for pivotally turning the blanks successively upon an axis within the area of the respective blanks from their transverse positions to positions of alignment with the web and feeding device. 45

9. A sanitary napkin machine comprising the combination with a support for a web of gauze and means for feeding such a web to said support from below, a pad feeding table aligned with said support, means on said table for aligning a pad with the direction of gauze feed over said support, means for discharging pads from said table longitudinally on to said gauze web at predetermined intervals, means for enfolding successive pads in said web, a pocketed pulley in the path of said web and pads, and means for holding the web and pads to said pulley for the inversion thereof, the pads registering with the pockets of the pulley for protection against the pressure of said holding means. 60

10. In a sanitary napkin machine, the combination with means for feeding a web of gauze and means for depositing pads at predetermined intervals thereon, of means for folding the margins of said web over said pad, means for severing 70

75

5 said web intermediate successive pads, means pocketed to receive the pads for inverting said web, and means for folding the ends of the severed web beneath the pad, whereby said ends are folded on the same face on which said margins have previously been folded.

10 11. In a sanitary napkin machine, the combination with means for feeding a web of gauze and means for depositing pads at predetermined intervals thereon, of means for folding the margins of said web over the face of the pads, a conveyor supporting the web and enfolded pads, a pulley about which said conveyor moves for the inversion of said web and the enfolded pads, said pulley being pocketed to receive the pads, means 15 for severing the folded web intermediate the enfolded pads, and means for folding the ends of the web beneath the pads adjacent the face on which the margins of said web were folded.

12. In a sanitary napkin machine, the combination with means for feeding a web of gauze, of means for feeding a web of filling material, means for blanking pads from said web of filling material, a pad feeding table adjacent the path 20 of said web of gauze, means for delivering the pads successively to the table, means associated with the table for the timed delivery of the pads to the gauze in predetermined spaced relation thereto, means for folding the margins of the 25 gauze over the successive pads, pocketed means for inverting the gauze and enfolded pads, a gauze severing device, and means for timing the operation of said gauze severing device with reference to the position of a pad in the web independently of said gauze feeding and pad blanking means.

13. The combination with means for making sanitary napkins, of a stacking device comprising a set of retractile supports, means for discharging sanitary napkins upon successive supports, means for advancing said supports along the path of napkin movement and simultaneously retracting them from each other, and a guide in the path of napkin advance upon said supports arranged to receive napkins upon the retraction of the supports.

14. In a sanitary napkin machine, a stacker comprising a skeleton throat adapted to receive the napkins, a series of coacting supports movable along opposite sides of said throat upon divergent paths, means for discharging the napkins on to said supports, and means for actuating said supports concurrently upon said paths, whereby to deposit said napkins in said throat.

15. In a device of the character described, the combination with a stacker having a throat, of a series of coacting supports movable along opposite sides of said throat upon divergent paths, means for feeding successive articles on to successive supports, means for moving the supports whereby to present a fresh pair of supports to receive each such article, said throat being sufficiently resistant to the movement of articles therein to require the interaction of the supports with articles previously deposited in said support as a means of propelling said articles under pressure through said throat.

16. In a sanitary napkin machine, the combination with a packing throat, of means for delivering the napkins successively therein and pressing the napkins therethrough under packing pressure exerted successively upon each napkin.

17. The combination with means for longitudinally feeding sanitary napkins, of a pair of chains 75 provided with sprockets about which adjacent

flights of said chains are movable in the same direction upon divergent paths, corresponding lugs on the respective chains providing supports on to which said napkins are individually fed in succession, means for advancing said chains in a direction to move said supports in unison for withdrawing them from beneath their respective napkins in the course of their advance, fingers between which the napkins are engaged as they advance, of a guideway with which said fingers communicate, said supports being adapted in releasing the napkins supported thereon to thrust preceding napkins through said guideway.

18. In a sanitary napkin machine, the combination with means for feeding a web of gauze and means for assembling and feeding a multiply web of cellucotton in the opposite direction, of means for transversely cutting successive end portions of the web of cellucotton during the continued advance thereof to separate filler blanks therefrom, means for turning said blanks upon their axes and advancing them toward the web of gauze in the general direction of cellucotton movement, means for reversing the direction of blank movement and delivering successive blanks 20 at intervals upon the web of gauze, means for folding the margins of said web of gauze about the blanks, means for inverting the web of gauze and its interfolded blanks, means for severing the folded web of gauze between the blanks 25 end-folded therein and for, folding over said blanks the severed ends of the gauze, and means for stacking for delivery the sanitary napkins thus made.

19. In a sanitary napkin machine, the combination with means for enfolded pads in a web of gauze, of means for feeding and inverting the gauze and enfolded pads comprising a pulley having pockets registerable with the enfolded pads, and a co-acting belt for holding the gauze and pads to the base of the pulley for a portion 40 of the rotation thereof, said pads being protected by the pockets of the pulley from the pressure of said holding means.

20. In a sanitary napkin machine, the combination with means for feeding a web of filler and a web of wrapping material upon a common center line, of a pad blanking head comprising relatively movable dies, said head being bodily movable along said center line, means for synchronously operating said head and the dies thereof for the blanking of pads from the web of filler material during the movement of the head with said web for delivering successive pads in spaced relation on to the web of gauze.

21. In a sanitary napkin machine, the combination with means for feeding a web of filler and a web of wrapping material upon a common center line, of a pad blanking head comprising relatively movable dies, said head being bodily movable along said center line, means for synchronously operating said head and the dies thereof for the blanking of pads from the web of filler material during the movement of the head with said web for delivering successive pads in spaced relation on to the web of gauze, said conveyor means having a portion beneath said head to receive pads blanked from the filler material, said conveyor means including mechanism for advancing said pads along said center line and concurrently turning said pads from positions transverse with respect to said line to positions of longitudinal alignment therewith.

22. The combination with means for continuously feeding a web of filler and a web of gauze 75

- upon a common center line, of means for punching pads transversely from the advancing end of the web of filler, means for advancing said pads along said center line while turning them into alignment therewith, and means for delivering said pads in spaced relation on to the gauze and enfolding them therein. 5
23. The combination with means for continuously feeding a web of filler and a web of gauze upon a common center line, of means for punching pads transversely from the advancing end of the web of filler, means for advancing said pads along said center line while turning them into alignment therewith, and means for delivering 10 said pads in spaced relation on to the gauze and enfolding them therein, together with means for inverting the gauze and enfolded pads, means for severing the gauze intermediate the pads, and folding the ends of the gauze on to the pads. 15
24. The combination with means for continuously feeding a web of filler and a web of gauze upon a common center line, of means for punching pads transversely from the advancing end of the web of filler, means for advancing said pads along said center line while turning them into alignment therewith, and means for delivering 20 said pads in spaced relation on to the gauze and enfolding them therein, together with means for inverting the gauze and enfolded pads, means for severing the gauze intermediate the pads, and folding the ends of the gauze on to the pads, said inverting means comprising a pulley pock- 25 eted to receive the pads to relieve pressure thereon. 30
25. The combination with means for continuously feeding a web of filler and a web of gauze upon a common center line, of means for punching pads transversely from the advancing end of the web of filler, means for advancing said pads along said center line while turning them into alignment therewith, and means for delivering 35 said pads in spaced relation on to the gauze and enfolding them therein, together with means for inverting the gauze and enfolded pads, means for severing the gauze intermediate the pads, and folding the ends of the gauze on to the pads, and means for stacking the completed sanitary napkins. 40
26. The method of making sanitary napkins which comprises feeding a web of filler material, supporting the web during the punching of pad blanks therefrom, punching blanks from the web during the movement thereof, feeding a strip of wrapping material, delivering the pad blanks in spaced sequence upon the moving web of filler material, enfolding the pads in wrapping material, severing the wrapping material between the pad blanks during the continued movement of the wrapping material, and folding the ends of the wrapping material upon the pad blanks. 45
27. The method of making sanitary napkins which comprises feeding a web of filler material, punching pad blanks successively from the end of such web during the movement thereof, feeding a strip of wrapping material, delivering the pad blanks successively upon the moving wrapping material in its first relation, folding the sides of the wrapping material over the pad blanks during the continued movement of the wrapping material, severing the wrapping material between successive pad blanks, and folding the cut ends of wrapping material on to the folded sides thereof. 50
28. The method of making sanitary napkins which comprises feeding a web of filler material, 55
- punching pad blanks successively from the end of such web during the movement thereof, feeding a strip of wrapping material, delivering the pad blanks successively upon the moving wrapping material in its first relation, folding the sides of the wrapping material over the pad blanks during the continued movement of the wrapping material, inverting the pad blanks and the en- 60 folding wrapping material to bring the folded sides of the wrapping material beneath the pad blanks, severing the wrapping material between pad blanks, and folding the severed ends of the wrapping material beneath the pad blanks, whereby to bring all folded portions of the wrapping material on to the same side of each pad blank. 65
29. The method of making sanitary napkins which comprises feeding a web of filler material, successively severing portions of the end of the web during the continued movement thereof to provide pads, feeding a web of wrapping material, delivering pads to the wrapping material and enfolding them therein during the continued feeding movement of the wrapping material to provide sanitary napkins, and delivering the finished napkins in a stack. 70
30. The method of making sanitary napkins which comprises feeding a web of filler material, punching pads transversely from successive end portions of the filler material during the continued movement thereof, continuing the advance of successive pads in the same direction while turning them to parallelism with the direction of advance, feeding a web of wrapping material and delivering successive pads thereto, enfolding the pads in the wrapping material, severing the wrapping material between pads, and delivering the completed sanitary napkins successively upon each other under moderate compression to comprise a stack for packaging. 75
31. In a machine for the manufacture of sanitary napkins or the like, the combination with means for continuously feeding a web of cellulocotton, of a die set including an apertured die base and a punch reciprocable to and from the base transversely of the path of advance of said web, means for reciprocating the punch in a direction to cut a blank from the web of cellulocotton and push the blank through the base, and means for reciprocating said die set along the path of web advance in synchronism with the reciprocation of said punch, whereby said base will move with the web during the severing of said blank. 80
32. In the method of making sanitary napkins, the steps of moving a web of filler material, carrying said web on a support moving therewith at substantially the same rate, and punching a blank from the web through the support while the support is in motion as aforesaid. 85
33. In the method of making sanitary napkins, the steps which comprise advancing a web of filler material, moving a support with the leading end portion of said web at substantially the rate and direction of web advance, and successively punching complete pad blanks from the advancing end of such material out of the plane of advance thereof while such material is in motion and in a direction transverse with respect to the path of said motion, whereby each successive blank is delivered transversely past the said support while the adjacent portions of the web remain supported thereby. 90

CURT G. JOA.
